UNITED STATES PATENT OFFICE.

WILLIAM H. BAKER, OF BRIDGEPORT, CONNECTICUT.

WARP STOP-MOTION.

1,026,941.

Specification of Letters Patent. Patented May 21, 1912.

Application filed July 9, 1910. Serial No. 571,253.

To all whom it may concern:

Be it known that I, WILLIAM H. BAKER, of Bridgeport, in the county of Fairfield and State of Connecticut, have invented 5 certain new and useful Improvements in Warp Stop-Motions, of which the following is a specification, reference being had to the accompanying drawings, forming part thereof.

10 This invention has reference to improvements in warp stop motions for looms, warp- ings and similar machines, and particularly to mechanical means by or through which the machine is stopped upon the breaking 15 of a warp thread or when one of said threads becomes unduly slack, or by or through which the occurrence of such fault is indicated.

One object of this invention is to so construct a mechanical warp stop motion of the 20 nature described that the same may be positive in its operation.

Another object of the invention is to facilitate the setting up of a warp with warp 25 stop motions of this nature.

Another object of the invention is to so construct a warp stop motion of this nature having a knocking off means controlled by 30 a feeler that two or more banks of drops may be used with a single feeler so that the movement of said feeler may be interrupted at or by the occurrence of a fault in the warp threads engaged with the drops of either bank.

35 Another object of the invention is to improve the means for supporting the movable mechanism the movement of which is adapted to be interrupted by the falling of a drop.

40 Other objects of the invention will appear from the following description.

The invention consists in the feeler controlled stopping mechanism in operative relation to the vibrator.

45 The invention also consists in the peculiar construction of the slide bar and its support.

The invention also consists in the peculiar construction of the mountings for the slide 50 bar support.

The invention also consists in such other novel features of construction and combinations of parts as shall hereinafter be more fully described and pointed out in the 55 claims.

Figure 1, represents a cross sectional view

of parts of a loom frame showing the improved warp stop motion, partially broken away, mounted in position. Fig. 2, represents a sectional view taken at right angles 60 to Fig. 1, showing parts of the knock off mechanism in relation to the feeler lever. Fig. 3, represents a plan view of the warp stop motion in relation to the lay and the breast beam of a loom showing the manner 65 in which the stopping lever is moved out of its retaining notch, one of the thread supporting rods being shown as swung outward as in setting up a warp. Fig. 4, represents an enlarged cross sectional view of portions 70 of the improved stop motion taken on line 4—4 Fig. 5 looking toward the right in said figure. Fig. 5, represents an enlarged sectional view taken on line 5—5 Fig. 4, looking toward the left in said figure. Fig. 6, 75 represents a similar view taken on line 6—6 Fig. 1. Fig. 7, represents a view similar to Fig. 5, showing one of the slide bars as arrested by a drop and the feeler impinging on the vibrator. Fig. 8, represents a cross 80 sectional view on larger scale, taken on line 4—4 Fig. 5 showing portions of the means for alining the drop devices to receive the slide bar and its support and also showing the construction of said support whereby 85 means may be inserted therein or thereon for preventing the engagement of the drop devices with the notches of the slide bar of its support when slide bar and support are passed through the slots of said drop devices.

Similar numbers of reference designate corresponding parts throughout.

As shown in the drawings, in its preferred form, 5 and 6 represent bracket arms adapted to be secured in the frame of a loom and to support the blocks 7 and 8 which carry the fault detecting mechanism by or through which the loom stopping mechanism is brought into action to stop the loom. Said 100 blocks 7 and 8 are respectively furnished with the members 10 and 11, of which member 10 is connected with block 7 by the arm 9, and said members 10 and 11 have seats 12 and 13 in which the respective ends of 105 the slide bar support 14—14 are received; accidental displacement of said supports 14—14 being prevented by the keepers 15 and 16 mounted to swing over the seats 12 and 13 and spring pressed toward such position.

The supports 14—14 are furnished with

longitudinal grooves extending from their upper edges, as shown in section in Fig. 8, and said upper edges of the support 14—14, preferably at both sides of said longitudinal groove, are furnished with notches 17—17 which may be of any suitable depth and dimensions; said supports 14—14 have also the transverse slots 18—18 located, near the ends of said supports. Slidably mounted in the longitudinal slot of each of said supports 14 is the slide bar 19 having a width less than that of said slot, as indicated in Fig. 8 the purpose of which will be herein-after described, and extending above the slotted edge of the bar 14 and furnished at said upper edge with the slots 20—20 which extend approximately to the bottom line of the slots 17—17. At the end portions of each slide bar 19 are removably secured the studs 21—21 which extend through the slots 18—18 of its related slide bar support 14.

Journalized in bearings in the block 7 is the rock shaft 22 having the lever 23 furnished with the rod 24, which is adapted to form a connection with some suitable moving part of the loom, whereby the vibration of said lever 23 may be effected to rock the shaft 22 to vibrate the yielding connection, secured to said shaft 22 by the collar 25, and comprising the flexible blades 26, 26 located at the sides of the spacing block 27.

Mounted to swing on the shaft 22 is the frame 28 having the upwardly extending member 29, furnished with the finger 30 which is engaged between the groups of blades 26, 26 and the depending arm 31 which extends downward below the supports 14, 14 and then upward between said supports at which point it is furnished with a cross-wise groove to receive the inwardly extending ends of the studs 21, 21 of the slide rods 19, 19 at this end of the supports 14, 14 so that, under normal conditions, the rocking of the shaft 22 effects the vibration of the arm 31 and the reciprocation of the slide rods 19, 19 but, if the movement of either of said slide bars is arrested, by a resistance sufficient to overcome the flexible blades 26, 26 the shaft 22 continues to rock without effecting the vibration of the arm 31.

Pivottally mounted on a stud extending from the lower portion of block 7 is the lever 36 having the arm 37 furnished with the feeler 38 which, therefore, is adapted to be vibrated in a path at right angles to and intersecting the path in which the lower portions 31' of the arm or vibrator 31 moves or vibrates. The lower end of lever 36 has the sleeve 39 in which one end of the connecting rod 40 is secured, the other end of said rod 40 being similarly secured in the sleeve 41 having the stud 42, forming a pivotal connection between said sleeve 41 and the arm 43 of the shaft 44 which latter is rotatably supported by the lay 1 of the loom

and has the short arm 45 furnished with the adjustable screw 46 in the nature of a knock off dagger, so called, so that the motion of the lay 1 is transmitted through arm 43 and rod 40 effects the vibration of lever 36 and its arm 37 whereby upon the movement of the lay 1 toward the breast beam 6 the feeler 38 is moved toward and across the path of that portion 31' of arm 31.

Attached to the sword 5 and to an extension from the rod 40 is the retraction spring 47 by which the lower end of arm 43 is normally held against the stop 55 of the sword 5, and the arm 45 is positioned as shown in full lines in Fig. 2. When, now, the movement of the feeler 38 is prevented the continued movement of the lay 1, carrying the bearings of shaft 44 toward the breast beam 6, will effect the swinging of arm 45 until its screw 46 is in line with pin 48 and, acting through said pin, effects the swinging of the protection lever 49 to knock the shipper lever 50 out of its retaining notch whereby the shipper lever is free to move to the loom stopping position.

Adjustably supported on extensions of the respective blocks 7 and 8 are the brackets 51 and 52 having respectively pairs of collars 53, 54 and 55, 56 in either pair of which the ends of the warp supporting rod 57 may be secured, and the respective seats 58, 59 for the rod 60. The brackets, 51, 52 have also the stops 61, 62 and pivotally mounted on said brackets adjacent to said stops, are the arms 63 and 64 which have the members 65, 66, adapted to be intercepted by said stops, and collars 69, 70 in which collars the ends of the warp supporting rod 71 are mounted while, to said blocks 67, 68 are removably secured the alining plates 72, 72.

In setting up a warp in a loom provided with this stop motion the arms 63 and 64 are swung to the positions shown in Figs. 3 and 6 with the warp threads *w* extending through the loom above rod 6 and the alining plates 72, 72. A drop device *d* of thin sheet metal and of any well known shape, suitable for the purpose and preferably having the lower open slot *e* and the upper closed slot *f* is now engaged with each of the threads by passing the lower open end of said drop down over one of said warp threads and, at the same time, over one of the alining plates 72 as shown in Fig. 8, this process being continued until all the warp threads are supplied with drops which are or may be arranged in one or more banks, each bank of drops being engaged with one of the plates 72, 72 and the slots *f* of all of said drops being in line. The slide bar supports 14, 14 are now, in succession, taken from their seats and the studs 21 at one end are removed to permit said support 14 and its slide bar 19 to pass through the alined slots *f* of a bank of drops *d* and, to

prevent the catching of the notches 20 of the slide bar against the edges of said slots *f*, I provide a thin ribbon or strip 73, Fig. 8, which is adapted to be received in the longitudinal groove of the slide bar support 14, at the side of said slide bar 19, owing to said groove being of greater width than the thickness of the slide bar, and said strip 73, extending beyond the notched edge of the slots *f* of the drops without catching. After such threading of the support 14 and its slide bar through the slots 14, the alining plates are released from their holding bolts and removed from the machine. The strip 73 is pulled out, endwise, and the ends of the support 14 are seated in their seats 12 and 13 in which they are held by the reaction of their spring pressed keepers 15, 16. When all of said slide rod supports 14 have been thus replaced the arms 63, 64 are swung to the position shown in Fig. 4 and the warp thread *w* and their drops *d* are supported by the rods 57 and 71.

With the drops *d*, *d*, sustained by the warp threads *w*, *w* in the normal position, the upper closed ends of the slots *f*, *f* of said drops *d*, *d* are above the notched edge of the slide bars 19, 19 and said bars are free to reciprocate under the vibration of the arm 31. If now, one of said warp threads breaks or becomes unduly slack the drop *d* of said warp threads falls until it meets the upper edge of its associated slide bar 19 or enters one of the notches 20 thereof, in the first case the fallen drop is held from lateral movement by the adjacent drops until the slide bar 19 moves sufficiently to bring one of its notches in registry with said fallen drop when said drop enters said notch and is then carried along over the edge of the slide bar support until it enters one of the notches 17 one edge whereof engages the drop and prevents the further movement of the drop which, in turn, arrests the movement of the slide bar 19. If the falling drop enters one of the notches of the slide bar 19 said drop is carried along until it engages one of the notches of the slide bar support 14 and so arrests the movement of the slide bar.

The notches 17 and 20 respectively of the support 14 and of the slide bar 19 are so proportioned and related that the movement of the slide bar 19 is arrested only when the lower end 31' of arm or vibrator 31 is in the path of the feeler 38 and, hence, said feeler impinges on said portion or member 31' whereby the movement of said feeler and its related parts, in this direction, is so limited that screw 46 is moved into line with pin 48 and, striking said pin, as above described, effects the release of the shipper lever.

While, preferably, I employ the member through which motion is imparted to the slide bar to arrest or limit the vibration of

the feeler I do not wish to limit the present invention thereto as I am aware that other means may be employed for this purpose.

The term "feeler" is herein used to designate broadly any element adapted to impinge against another element to limit the movement of a member of a mechanism by or through which a stopping means is brought into operation to ultimately effect the stopping of the loom or other machine.

One of the notched edges of the support 14 may be considered as a holding means for the riding strip 73 as said strip is held in position thereby.

To the best of my knowledge I am the first to operate the protection rod or lever of a loom through a warp stop motion to effect the knocking or moving of the shipper lever out of engagement with its retaining notch or device to permit said shipper lever to move to the loom stopping position and I desire to claim this feature broadly.

Having thus described my invention, I claim as now and desire to secure by Letters Patent—

1. A warp stop motion comprising a notched bar slidably mounted, a vibrator pivotally mounted and connected with said bar, a rock shaft having a yielding connection with which said vibrator is engaged, drop detectors for arresting the movement of said bar and its vibrator under abnormal conditions, and a feeler mounted to move in a path intersecting the path of said vibrator.

2. A warp stop motion comprising a notched bar slidably mounted, a vibrator pivotally connected with said bar and having an arm furnished with a lateral projection, a rock shaft, a spacing block on said rock shaft, yielding plates secured to said spacing block between which said projection is engaged, drop detectors for arresting the movement of said notched bar and its vibrator under abnormal conditions, and a feeler coöperating with said vibrator and mounted to move in a path intersecting the path of said vibrator.

3. A warp stop motion for looms comprising a notched bar slidably mounted, a pivotally mounted vibrator to reciprocate said bar, operating means for said vibrator including a yielding connection, means for arresting the movement of said notched bar under abnormal conditions, a feeler mounted to move in a path intersecting the path of said vibrator and coöperating with said vibrator and having a lever, means for operating said lever from the lay of the loom such means including a dagger, the knock off lever, an arm pivotally mounted on the breast beam and adapted to act against the last mentioned arm and said dagger.

4. A warp stop motion comprising a pair of notched bars slidably mounted, means for reciprocating the said bars under normal

conditions including a pivotally mounted member movable in unison with said bars, a rock shaft, two flexible plates upon said rock shaft in engagement with the said movable member, drop detectors for arresting the movement of either of said bars and said movable member under abnormal conditions,

a feeler coöperating with said movable member and mounted to move in a path intersecting the path of said movable member.

WILLIAM H. BAKER.
